THREE LEGGED MULTI-HEIGHT GOLF BALL TEE

Robert L. Reed, 6039 E. 57th Place, Tulsa, Okla.
74135, and Cyril L. Spencer, 7910 W. County Club
Drive, Apt. 4, Overland Park, Kans. 66212

Filed Nov. 18, 1974, Ser. No. 524,857

Term of patent 14 years

Int. Cl. D21—02
U.S. Cl. D34—5 GT

FIG. 1

FIG. 2

FIG. 1 is a perspective view of a three legged multi-height golf ball tee, showing our new design; and

FIG. 2 is a front elevation view of the three legged multi-height golf ball tee of FIG. 1.

We claim:

The ornamental design for a three legged multi-height golf ball tee, as shown and described.
